UNITED STATES PATENT OFFICE.

FRANK J. VENNING, OF PITTSBURG, PENNSYLVANIA.

TROLLEY FROG AND CROSSING.

No. 914,207.

Specification of Letters Patent. Patented March 2, 1909.

Application filed April 15, 1908. Serial No. 427,170.

To all whom it may concern:

Be it known that I, FRANK J. VENNING, a citizen of the United States of America, residing at Pittsburg, in the county of Allegheny and State of Pennsylvania, have invented 5 certain new and useful Improvements in Trolley Frogs and Crossings, of which the following is a specification, reference being had therein to the accompanying drawing.

10 This invention relates to trolley frogs and crossings, and more particularly to wearing plates designed for right and left hand frogs, three-way frogs, adjustable and insulated frogs, draw-bridge frogs, and that type of 15 overhead construction ordinarily employed for guiding a trolley wheel at the intersection or crossing of trolley wires.

The primary object of my invention is to provide a wearing plate that can be easily 20 and quickly attached to a frog to increase the use or longevity of the same.

Another object of this invention is to provide an attachment for frogs that will receive 25 the wear and tear of the trolley wheel, and prevent the frog from being injured.

My invention aims to obviate the necessity of continuously renewing frogs in connection 30 with the overhead construction of a street railway, it being a well known fact that the endurance of the present type of frogs is of but a short period of time, and that considerable time, labor and money is expended in the maintenance of overhead construction work. It is with this fact in view that I have 35 devised the wearing plate forming the subject matter of this application, the plate being designed to relieve the frog of the wear to which the latter is ordinarily subjected, and thus materially increase the longevity and 40 use of the frog.

With the above and other objects in view which will more readily appear as the invention is better understood, the same consists in the novel construction, combination and arrangement of parts to be presently described and then specifically pointed out in the appended claims.

In the drawings:—Figure 1 is a bottom plan view of a left hand frog equipped with my wearing plate, Fig. 2 is a longitudinal sectional view of the same, taken on the line $y-y$ of Fig. 5, looking in the direction of the arrow. Fig. 3 is a plan of a left hand wearing plate, Fig. 4 is a plan of a right hand wearing 55 plate, Fig. 5 is a top plan view of the frog as shown in Fig. 1 with the wearing plate at-

tached thereto. Fig. 6 is a cross sectional view taken on the line $x-x$ of Fig. 5, looking in the direction of the arrow. Fig. 7 is a bottom plan of a cross-over, which can be of the 60 insulated type, Fig. 8 is an elevation of the same, Fig. 9 is a plan of a wearing plate designed for a crossover, Fig. 10 is a plan of a similar plate designed for an adjustable crossover, and Fig. 11 is a bottom plan of an 65 adjustable crossover equipped with my wearing plate.

The frog shown in connection with my improvement is of an ordinary type and comprises a body portion 1, having main tongues 70 or runways 2, 2^a at opposite ends, the wider end of the frog also having a switch tongue or runway 3. The frog body is provided on its upper face with strengthening ribs 4 which taper off toward each end and terminate in the different tongues or runways as clearly shown by reference to Figs. 5 and 6. These tongues or runways have the trolley or conductor wire 5 secured thereto in any desired manner, as by soldering in the runways or tongues, or by nuts (not shown) engaging the split threaded studs 6 carried by the tongues or runways. 75

The body 1 of the frog is provided with pull-off rings 7, to which are attached cables 85 8 for supporting the frog overhead. The frog just described is of a form generally used by electric railways, and reference will now be had to my attachment or improvement, which is used in connection with the 90 frog to prevent the same from the wear and tear in the travel of a trolley wheel from one runway or tongue to another.

My attachment comprises what I term a wearing plate 9, which is shaped to fit the 95 under face of the pan or body of the frog and lie between the depending side flanges 10 of said frog body, this plate extending to the ends of the pan or body, where its ends provide lugs that bend upwardly and rearwardly upon the ends and upper face of the pan or body, as at 11, to retain said plate in engagement with the frog. 100

The plate 9 is constructed of strong and durable metal having wearing qualifications 105 sufficient to insure considerable use of the plate before the same is worn or cut by the flanges of the trolley wheel passing over the same.

In order that the wearing plate can protect that portion of the frogs subjected to 110 the action of the wheel flanges, and in order

that the plate can be easily and quickly secured to the frog, I form the same with bifurcated ends or extensions 12, adapted to extend along the runways or tongues to the ends of the frog, where the extensions are clenched upon the ends of the frog, as previously described.

The wearing plate just described is designed for right or left hand frogs or can be used in connection with a V-frog, and reference will now be had to Figs. 5 to 9 inclusive, wherein I have illustrated a wearing plate particularly designed for fixed, adjustable or insulated crossings. The crossing illustrated in Figs. 5 and 6 comprises a circular body or pan 13 having diametrically opposed runways or tongues 14 and a central pin 15. The wearing plate which I use in connection with this crossing (see Fig. 7) is circular and is provided with a circular opening 16 to clear the pin 15 and is cut away as at 17, to clear the runways or tongues 14. The wearing plate is provided with radially disposed lugs 18, adapted to be bent upwardly and over the edges of the pan or body 13, similar to the ends of the extensions 12, of the plate 9.

In Fig. 8 of the drawings I have illustrated a wearing plate 19 provided with a plurality of radially disposed lugs 18, this wearing plate being particularly designed for an adjustable or insulated crossing, such as illustrated in Fig. 9 of the drawings. Irrespective of the angularity of the tongues or runways, some of the lugs 18 can be employed for holding the wearing plate 19 in engagement with said crossing, and the lugs that are not used for holding the plate can be cut off or left to align with the tongues or runways of the crossing.

It is apparent that I have devised a novel wearing plate for the present type of frogs and that said plate can be easily and quickly attached to a frog, even though the latter has already been installed. This is a desideratum in connection with the maintenance of overhead construction, as considerable time is consumed and delay in traffic incurred in installing a new frog.

Another characteristic of my invention is the simple and economical construction which permits of the wearing plates being produced at a comparatively small cost.

The invention as above described is susceptible to such structural changes as are permissible by the appended claims.

Having now described my invention what I claim as new, is:—

1. The combination with a frog having a pan and runways, of a metallic wearing plate detachably mounted upon said frog, said wearing plate having extensions adapted to extend along said runways and be bent to engage the ends of said frog.

2. The combination with a crossing, of a metallic wearing plate detachably mounted thereon, said plate having lugs adapted to be bent upwardly and upon said crossing, substantially as described.

3. The combination with a frog, of a metallic wearing plate detachably connected thereto, and means carried by said plate for fastening the same to said frog.

4. As a new article of manufacture, a metallic wearing plate shaped to fit within a frog pan and having an incut at each end providing tongues to afford means for securing the plate to the frog pan.

5. In combination with a frog having a pan, a wearing plate detachably secured to the underneath face of the pan.

6. In combination with a frog having a pan, a metallic wearing plate fitted against the underneath face of the pan and having arms at its end adapted to be bent over against the upper face of said pan.

7. In combination with an overhead frog having a pan, a wearing plate shaped to fit against the underneath face of the pan, and means at the ends of said plate for detachably securing the same to the frog pan.

In testimony whereof I affix my signature in the presence of two witnesses.

FRANK J. VENNING.
